(57) **CLAIM**

The ornamental design for a knife handle, as shown and described.

DESCRIPTION

FIG. 1 is a perspective view of the knife handle of this invention.

FIG. 2 is a top plan view of the knife handle of this invention.

FIG. 3 is a side elevational view of the left side of the knife handle of this invention.

FIG. 4 is a bottom plan view of the knife handle of this invention.

FIG. 5 is a side elevational view of the right side of the knife handle of this invention.

FIG. 6 is a front elevational view of the knife handle of this invention; and,

FIG. 7 is a rear elevational view of the knife handle of this invention.

The broken line disclosure is for illustrative purposes only and forms no part of the claimed design.
